UNITED STATES PATENT OFFICE.

DECENZIO LO PRESTI SEMINERIO, OF TURIN, ITALY, ASSIGNOR TO SOCIETA ITALIANA
REGISTRATORI SIR, OF TURIN, ITALY, A COMPANY OF ITALY.

PRINTING DEVICE FOR CASH-REGISTERING MACHINES.

Application filed May 9, 1924. Serial No. 712,023.

To all whom it may concern:

Be it known that I, DECENZIO LO PRESTI SEMINERIO, subject of the King of Italy, residing at Turin, Italy, have invented certain new and useful Improvements in Printing Devices for Cash-Registering Machines, of which the following is a specification.

The present invention relates to cash registering machines, and more particularly to devices used in cash registering machines for supporting and carrying a paper tape and causing it to be printed upon by printing means comprised in the machine for the purpose of recording the results of the operations effected in said machine.

The invention involves a unit removably arranged in the machine and comprising means for supporting and feeding a paper tape and for mounting the unit itself in the machine and connecting it with parts of the machine, which means enable said device to be shifted in the machine into position to facilitate the insertion of the paper tape, and to be removed from said machine, the means for the actuation of the device by cash registering machine parts being arranged to permit such said shifting movement without dismantling or removing parts.

Further, the invention embodies improved means for supporting the paper tape roll and for feeding and winding up the same.

On the annexed drawing is shown by way of example an embodiment of the present invention, and:

Figure 1 is a front view of the same in position in the machine;

Figure 2 is a side view;

Figure 3 is a view from the back with parts in a different position with respect to Figure 1;

Figure 4 is a central section of the spools for the paper tape;

Figure 5 is a detail view of a position-determining sleeve.

The device comprises a supporting plate 1 provided with a hub 2 loose on a spindle 3 mounted in the machine frame. In sleeves 61 and 71 (Fig. 4) fixed to said plate 1 are journaled spindles 6 and 7 having grooved pulleys 4 and 5 secured to them which are adapted to carry the winding and unwinding spools 8 and 9 for the paper tape.

On the plate 1 is also mounted a roller 55 11 on which passes the paper tape, shown conventionally by a dotted line 100, which tape is held in position by a pressing roller 12. Said roller 11 produces the paper feed at each operation and for this purpose it has 60 connected to it a ratchet pinion 14 engaged by a check pawl 15 and operated by a driving pawl 16 pivoted on an arm 17 which is rotatable around the axle 11' of the roller 11.

A crank lever 18 acted on by a spring 29 is pivoted concentric with the roller 11, on the rear face of the plate 1. On the lower arm 18' of said crank lever 18 is pivoted at 19' an arm 19 carrying the inking 70 roller 20 and held in the position illustrated by a spring 21 attached to arms 19 and 18' respectively, and a positioning pin 22.

On the common pivot or axle 11' of the 75 roller 11 and of the crank lever 18 is also pivoted an arm 23 which is controlled by a hand lever 26, a crank lever 25 rigidly connected with lever 26 and arranged behind the plate 1, and a rod 24 connecting said 80 lever 25 with a tail 23' of the arm 23. By means of the above described parts the said arm 23 may be oscillated around its pivot and carried at will into the position of Figure 1 in which it projects to one side of the 85 plate 1, or into the position of Figure 3 in which it lies behind said plate. A spring 27 attached to arm 25' of lever 25 and to a stationary pin 37 on plate 1 acts to keep the lever 26 and associate parts in the desired position, said lever 26 being stopped in position by pins 102 on a quadrant 103.

The arm 23 has a pin 28, and a spring 29 attached to a stationary stud 32 keeps a projection 30 of the crank lever 18 in contact 95 with said pin when the arm 23 is in the position of Figure 1, while, when the arm 23 is in the position of Figure 3, the said spring 29 moves said lever 18 behind the arm 23, it being engaged in this position by a pin 28' 100 projecting from the rear face of the plate 1.

The previously mentioned pressing roller 12 is carried by an arm 31 pivoted on said stud 32 of the plate 1 and actuated by a spring 33, which is attached to plate 1 and to a pin 34 on the said arm 31. The pin 34 may engage (see Figure 3) an abutment 35 on an arm 36 pivoted on pin 37 when it is

desired to hold the roller 12 away from the roller 11 prior to positioning the paper tape in the machine; such engagement being effected by rocking said arm until its pin contacts with the abutment, the arm 36 being thereafter kept in engaged position by a spring 36'.

Finally, at the top portion of the plate 1 is arranged a stud 38 on which is engaged a 10 fork 39 having at its opposite end a hook 40 and a manipulating knob 41; a spring 42 connected with the stud 38 and the fork 39 acts to move the hook 40 towards the stud 38. On the machine frame is arranged a 15 spindle 43 on which is mounted a loose and slidable sleeve 58 having two adjacent grooves 58'-58'', into the first one of which projects the edge of the plate 1, as shown in Fig. 1, while in the second one is engaged 20 the hook 40 (Fig. 3); the plate 1 is thus connected with the spindle 43 by the intermediary of spring 42 which holds it resiliently in the position of Figure 1, while the sleeve 58 being free to slide on the spindle 43 permits 25 the plate 1 to be shifted in the direction of the axis of the spindle 43. By means of the knob 41 the hook 40 may be depressed and thereby released from the sleeve 58 and spindle 43, and said knob may thereupon be 30 engaged in the recess 44, the plate 1 being then entirely free from the spindle 43 while the hook 40 is held in position on the plate.

As shown in Figure 4, the winding up 35 spool for the printed paper comprises a core 45 and a removable flange 46 having a hub 46' and a sleeve 46'' which are located on the spindle 6 and rigidly connected therewith by means of a set screw 47; on said flange is pivoted at 48' an arm 48 operated 40 by a spring 49 (Fig. 1) and having a tongue 50 which extends over the core 45 and grasps the first tape convolution on the same.

In the cash registering machine, the 45 device is mounted to rotate around the fixed spindle 3 and is kept usually in the position of Figure 1 by the spring 42 connected with the stud 38, the hook 40 being engaged with the sliding sleeve 58.

The feed roller 11 is located opposite a 50 printing drum 13 having printing types on its periphery, and the arms 18 and 23 are designed to be engaged by cams 51 and 52 carried by a disk 53 which is driven by a shaft 54; the drum 13 and the shaft 54 are actuated 55 by the mechanism of the cash registering machine at the required time and in a suitable manner, the arrangement and operation of the parts 13, 53 and 54 not being described in detail as having no bearing on the 60 actual invention.

Finally, the machine frame has a pin 55 (Fig. 1) positioned between projections or teeth 17' and 17'' on the arm 17.

It being assumed that a roll of paper tape 65 has been wound up on spool 9 and then led

through the device as shown by the dotted line 100 so as to pass across the guide roller 56, then around the roller 11 and then between said roller 11 and the presser roller 12, and, finally, that its end has been grasped 70 between the core 45 and tongue 50 of the spool 8, and that the several parts are in the usual position as shown by Figure 1, the operation is as follows:

When the disk 53 is rotated by the machine drive, the cam 51 engages the arm 18 and causes it to rock around its pivot 11', the plate 1 being left stationary. Because of this oscillation of the said arm 18, the inking roller 20 is carried onto the printing 75 drum 13 and then as soon as the cam 51 has released the arm 18, the parts are carried back into usual position by the spring 29. The impact of the roller 20 on the drum 13 is cushioned by the arm 19 carrying said 80 roller being rotatably mounted on the arm 18 and held in position by the spring 21.

This yielding mounting of the inking roller 20 permits it to be brought, owing to the oscillation of arm 18, opposite the types 90 which have to leave their impressions on the paper during the operation in question; said roller striking first of all against a line of types which are outside of the printing line and rolling over the successive teeth of the 95 printing drum 13.

On the rotation of the disk 53 being continued, the cam 52, which is on the opposite side of the disk 53 from the cam 51, is caused to act on the arm 23 so as to rock 100 plate 1 bodily, with the parts carried by it, around the stationary spindle 3, against the action of the spring 42, said arm 23 being held in the illustrated position with respect to plate 1 by the rod 24 and levers 25-26. 105 In said oscillation the roller 11 with the paper tape thereon, is carried against the printing drum 13 and thus the types of the drum 13, which were previously inked in the described manner, are caused to print 110 on the paper, said roller 11 acting at the same time both as a feeding and as a platen roller.

During the oscillation of the plate 1, in the forward motion of the same, the tooth 115 17' engages the stationary pin 55 and therefore the arm 17 is caused to oscillate with respect to plate 1, its pawl 16 being moved back one tooth space with respect to the ratchet pinion 14 which is prevented from 120 rotating by the pawl 15.

As soon as the cam 52 releases the arm 23, the spring 42 causes the plate 1 to move back into the position of Figure 1; during this motion the tooth 17'' of the arm 17 is 125 engaged by the pin 55 and therefore said arm is again caused to oscillate with the pawl 16 which drives the pinion 14 and the drum 11 and moves forward the paper tape to feed a fresh portion of the same in front 130

of the printing drum for the next operation.

When it is desired to put the device out of operation, it is sufficient to move the hand lever 26 to rock the crank lever 25 which raises the arm 23 by means of the rod 24 and carries said arm into the position of Figure 3 in which it is out of cooperation with the cam 52; then the spring 29 moves 10 back the arm 18 until the tooth 30 which is no longer engaged by the pin 28 on the arm 23, comes in engagement with the pin 28' on the plate 1 and the operation of the inking roller is thus prevented. The spring 15 27 acting on the arm 25' of lever 25 may produce a stress in opposite directions with respect to the fulcrum of said lever and so as to keep the said lever and parts connected therewith in either position imparted 20 to them by the manipulation of lever 26.

As above described, the roll of paper to be printed is located on the spool 9 and the paper passes across the guide roller 56 and around the feeding and platen roller 11 25 against which latter it is pressed by the pressing roller 12, and finally said tape winds up on the drawing spool 8; this spool 8 has its pulley 4 connected by a cord or other endless flexible element 10 with the 30 driving pulley 5 on the unwinding spool 9, said cord passing around a grooved guide roller 104 loose on the spindle 105 connecting the lever 25 with the lever 26. The paper tape on being drawn by the roller 11 35 actuated by the ratchet 14 and pawl 16, causes the rotation of the spool 9 and pulley 5 and as this pulley has a larger diameter than the pulley 4 of the winding-up spool 8, it acts to drive the spool 8 through a 40 larger angular extent than that the spool 9 has been moved, the core 45' of said spool 9 being rigidly connected with the spindle 7 by means of a projection 9' on the pulley flange and a set screw 47'.

45 By shifting the operating lever 26 to carry arms 18 and 23 into the position of Figure 3 in which they are out of the path of the cams 51 and 52 when the disk 53 is rotated, the whole device may be freely moved along the spindles 3 and 43, on which latter slides the sleeve 58 engaged with the plate 1 in the hereinbefore described manner.

The device may thus be shifted from the 55 usual position shown in Figure 2 in which it is resiliently held by a spring stud 60 engaging a groove 59 of the spindle 3, up to a position near the front end of the spindles 3 and 43 where it is held by said stud 60 60 which then enters a groove 59' (Fig. 2) in the said spindle 3; the device is thus held in a position in which it is easy to introduce the paper in position.

To remove the device from the cash registering machine it is sufficient to release the 65

hook 40 from the groove 58" of the sleeve 58 and engage the knob 41 in the plate notch 44; the plate 1 may then be released from the sleeve 58 and the entire device may be withdrawn by grasping the milled portion 2' of 70 the hub 2.

Of course the insertion of the device in the machine is effected by similar manipulations made in reverse order.

For locating the paper tape in position 75 the pressing roller 12 is held removed from the feeding roller 11 by engaging the pin 34 of its arm 31 with the projection 35 of the lever 36, while the spring 33 moves said roller back and keeps it in operative position as soon as the lever 36 is released. Wings 11" are provided on the roller 11 for the purpose of manipulating it as it may be required when setting the paper tape in position. In order to engage the paper tape 80 on the core 45 of the wind-up spool 8 it is sufficient to wind the end of the tape on the said core and then locate in position the flange 46 while acting on the arm 48 to keep its extension 50 removed from the core; as 85 soon as the arm 48 is released, its spring 49 forces said extension 50 against the paper convolution and holds it in position.

The device according to the present invention provides a single unit having all 90 the parts for its operation and mounting on the cash registering machine, including the return member and respective connections, which consists of the spring 42 and hook 40, permanently connected with the said supporting plate. 100

What I claim as my invention and desire to secure by United States Letters Patent is:—

1. A paper tape feeding and printing device for cash registers, comprising an oscillatory supporting member; winding and unwinding spools carried thereby; a feed roller for the tape located between said spools; means for rotating the winding 105 spool; an arm pivoted on said supporting member; an inking member carried by said arm; means actuated by a part of the cash register drive for bringing said inking member into operation; means actuated by a part of the cash register drive for swinging the supporting member in one direction; means for printing on the tape during such swinging movement; means for effecting the return movement of said inking and supporting members; and means for automatically rotating the feed roller during said return movement. 110

2. A paper tape feeding and printing device for cash registers, comprising an oscillatory support, tape carrying and feeding means mounted thereon and including a combined feed and platen roller around which the tape passes; a settable printing element; a pawl-and-ratchet device con- 125 130

- 5 nected to drive said roller; an arm pivoted on said supporting member; an inking member carried by said arm; means actuated by a part of the cash register drive for swinging said inking member relatively to said support and against said printing element; means actuated by a part of the cash register drive for swinging said support bodily in a direction to move said roller against said 10 printing element; and means for automatically operating said pawl-and-ratchet device during the return movement of the support.
- 15 3. A paper tape feeding and printing device for cash registers, comprising an oscillatory support; tape carrying and feeding means mounted thereon and including a combined feed and platen roller around which the tape passes; a settable printing element; a ratchet secured to said platen roller; a pawl-carrying arm pivoted to said support for coaction with said ratchet; a roller-carrying arm pivoted on said support; an inking roller carried by the last-named 20 arm, said last-named arm having a portion thereof engageable by a part of the cash register drive to swing the inking roller against the printing element; an actuating arm attached to said support and engageable 25 by a part of the cash register drive to swing the support in a direction to move the platen roller against said printing element; and means for automatically operating the pawl-carrying arm during the return movement 30 of the support.
- 35 4. A paper tape feeding and printing device for cash registers, comprising an oscillatory support; tape carrying and feeding means mounted thereon and including a combined feed and platen roller around which the tape passes; a settable printing element; a ratchet secured to said platen roller; a pawl-carrying arm pivoted to said support for coaction with said ratchet; a 40 roller-carrying arm pivoted on said support; an inking roller carried by the last-named arm, said last-named arm having a portion thereof engageable by a part of the cash register drive to swing the inking roller against 45 the printing element; an actuating arm attached to said support and engageable by a part of the cash register drive to swing the support in a direction to move said platen roller against said printing element after 50 the contact of the inking roller with the printing element has taken place; and means for automatically operating the pawl-carrying arm during the return movement of the support.
- 55 60 5. A paper tape feeding and printing device for cash registering machines, comprising a single unit removably supported in the machine and embodying inking means and tape carrying and feeding means including a platen roller around which the tape passes,

said inking means and platen roller adapted to be brought successively into contact with a settable printing element, and means for rotating said roller to effect the feed of the tape; said unit adapted to be swung automatically in one direction by a part of the cash register drive to effect such printing contact, and said roller-rotating means being automatically operated during the return movement of the unit.

said arms into inoperative position with relation to said drive parts to prevent their actuation thereby.

11. A tape feeding and printing unit, according to claim 10, in which the means for springing one of said arms comprises a hand lever, a bell crank operated thereby, and a connecting rod between the bell crank and the said arm for rocking the latter about its pivotal axis.

12. In a cash register, a tape feeding and printing unit comprising a supporting member; tape carrying and feeding means mounted thereon; a stud on said supporting member; a spring attached to said stud; a reciprocatory fork engaged with said stud and connected with said spring, said fork having a hook for releasable engagement with a stationary part of the cash register; and cooperating means on said fork and supporting member for holding the former in position on the latter when said hook is released.

13. In a cash register, a tape feeding and printing unit comprising a supporting member; tape carrying and feeding means mounted thereon; a sleeve slidably mounted on a fixed spindle in the machine and formed with a pair of spaced grooves, in one of which an edge of said supporting member is removably engaged; a stud on said supporting member; a spring attached to said stud; a reciprocatory fork engaged with said stud and connected with said spring, said fork having a hook releasably engaged in the other groove in said sleeve; and cooperating means on said fork and supporting member for holding the former in position on the latter when said hook is released.

14. In a cash register, a tape feeding and printing unit comprising a supporting member; tape carrying and feeding means mounted thereon; a stud on said supporting member; a spring attached to said stud; a reciprocatory fork engaged with said stud and connected with said spring, said fork having a hook for releasable engagement with a stationary part of the cash register;

and a projection on said fork for removable engagement in a notch in the supporting member to hold the fork in position thereon when said hook is released.

15. In a paper tape feeding and printing mechanism for cash registers, a single unit removably supported in the machine and embodying an oscillatory support; tape carrying and feeding means mounted thereon and including a platen roller; a pivoted arm; inking means carried by said arm; a pawl-and-ratchet device to drive the tape feeding means; a settable printing element; means actuated by a part of the cash register drive for swinging said arm to carry said inking means against said printing element; means actuated by a part of the cash register drive for swinging the oscillatory support bodily in a direction to move the platen roller against the printing element; and means for automatically operating said pawl-and-ratchet device during the return movement of the support.

16. In a paper tape feeding and printing mechanism for cash registers, an oscillatory unit removably supported in the machine and embodying tape-carrying and feeding means including a platen roller; a pivoted arm; inking means carried by said arm; a settable printing element; an arm connected with the first-named arm and adapted to be actuated by a part of the cash register drive to swing said inking means against said printing element; an arm adapted to be actuated by a part of the cash register drive for swinging the unit bodily in a direction to move the platen roller against the printing element; means on the last-named arm against which said first-named arm is pressed; and means for defining the position of said last-named arm in the unit, said defining means enabling the said arm to be swung into inoperative position with relation to the associated drive part to prevent the actuation of the mechanism.

In testimony whereof I affix my signature.

DECENZIO LO PRESTI SEMINERIO.
